EXHAUSTING MECHANISM

Robert W. Van Valzah, Riverside, Ill., assignor to
Western Electric Company, Incorporated, New
York, N. Y., a Corporation of New York

Application March 5, 1932. Serial No. 596,989

7 Claims. (Cl. 126—56)

This invention relates to an exhausting mechanism, and more particularly to an exhausting mechanism for furnaces operable in more than one position.

In furnaces of the above type, one form of exhausting mechanism heretofore employed included a hood sufficiently large enough to extend completely over the top of the furnace at all operating positions thereof. The large hood was found objectionable due to its unsightly appearance and its obstruction of light and also due to an excessive amount of heat being dissipated into the room in which the furnace is located.

An object of the present invention is to provide a more simple, efficient and practical mechanism for exhausting gases from a furnace operable in more than one position.

In accordance with one embodiment, the invention contemplates an exhausting mechanism for car-type furnaces comprising a stationary stack and a hood fixedly mounted upon and movable with a furnace and completely enveloping the exhaust vent of the furnace, the hood being provided with a plurality of damper-controlled openings arranged to be selectively moved into registry with the stack by movement of the furnace into one or another of its operating positions, and the dampers being controlled by means actuated by the movement of the furnace.

The invention will be more fully understood from the following description taken in connection with the accompanying drawing, in which

Fig. 1 is a fragmentary elevational view of a car-type furnace having an exhausting mechanism embodying the features partly in section, and

Fig. 2 is a sectional view of the exhausting mechanism taken along the line 2—2 of Fig. 1.

Referring now to the drawing wherein like reference numerals designate similar parts in both views, numeral 10 designates a stationary stack disposed in a suitable position so that damper controlled openings of an exhausting mechanism indicated generally at 11 may be moved into registration therewith when a furnace 12 upon which the exhausting mechanism is mounted is moved into one or another of a plurality of operating positions. The exhausting mechanism 11 consists of an insulated hood 13 having damper controlled openings 14 and 15 disposed in the top wall adjacent the ends thereof, the openings being provided with dampers 16 and 17, respectively, which are fixed to shafts 18 and 19, respectively, rotatably journaled so that the dampers may be swung into open or closed positions.

Mounted upon the shafts 18 and 19 at one side

of the hood 13 are damper actuating cams 22 and 23, respectively, which are normally urged in clockwise and counterclockwise directions, respectively, by springs 24 and 25, respectively, to normally urge the dampers into closed positions. 69 The cam 22 is cut away to provide a tapered roller engaging surface 27 positioned to engage a roller 28 which is rotatably carried by a bracket 29 fixed to the stationary stack 10. The cam 23 is cut away to provide a tapered roller engaging 65 surface 30 positioned to engage a roller 31 which is also rotatably carried by the bracket 29. Flanged guides 32 are mounted upon the hood 13, extend longitudinally thereof and pass upon each side of the stack 10 as the furnace is moved 70 from one operating position to another.

The exhausting mechanism 11 is mounted upon the furnace 12 in any suitable manner such as shown in Fig. 1, and is connected to a retort vent 35 at an aperture 36 in the bottom wall of the 75 hood 13, the exhaust vent 35 extending into the furnace 12 and communicating with a retort chamber 37 of the furnace.

During the operation of the mechanism, the furnace 12 may be loaded in any suitable manner with material to be treated; furthermore, any suitable means may be employed for moving the furnace from one operating position to another. As shown in Fig. 1 the furnace together with the exhausting mechanism is in its farthest position to the left and while in this position the damper 16 is held closed by the spring 24 and the damper 17 is held in its open position against the tension of the spring 25 by the roller 31. While the exhausting mechanism is in this position the opening 15 of the hood 13 is in general alignment with the stack 10 allowing gases to escape from the retort chamber 37 through the exhaust vent 35, the aperture 36, to the right through the hood 13, through the opening 15 and pass upwardly through the stack 10. 85 90 95

When the furnace 12 with the exhausting mechanism 11 is moved to the right (Fig. 1), the cam 23 is moved in a counterclockwise direction by the spring 25 to move the damper 17 into closed position as the shaft 19, upon which the cam 23 is mounted, moves to the right. During the movement of the furnace and the exhausting mechanism from one position to another, such as from the left to the right, the dampers 16 and 17 are in closed positions; that is, as soon as the exhausting mechanism with the furnace is moved a sufficient distance to allow the damper 17 to close. While the exhausting mechanism is reaching the end of its travel 100 105 110

to the right, the surface 27 of the cam 22 engages the roller 28, and during the remainder of the movement of the exhausting mechanism the cam 22 is rotated in a counterclockwise direction 5 until the damper 16 is moved about the shaft 18 from its horizontal and closed position to a vertical and open position. The opening of the damper 16 conditions the exhausting mechanism so that gases may escape from the furnace 10 through the exhaust vent 35 through the aperture 36, through the hood 13 to the left, through the opening 14 and upwardly through the stack 10, which is in general alignment with the opening 14 when the exhausting mechanism with the furnace is in its farthest position to the right. The guide 32 aids in assuring the alignment of the stack 10 with the openings 14 and 15 when the exhausting mechanism 11 with the furnace 12 is either in the right or left operation positions. 15

The exhausting mechanism is relatively narrow as shown in Fig. 2 and need not extend in its length beyond the side walls of the furnace to cause an obstruction of light. Furthermore, a 20 more efficient association is made between the furnace and the stack at each operating position than is possible with the original unsightly type of exhausting mechanism which extends over the entire area covered by the furnace in its 25 operating positions.

Although this exhausting mechanism has been described as being applied to a furnace, it should be understood that it may be applied to devices of other types for exhausting gases therefrom 30 without departing from the spirit and scope of the present invention.

What is claimed is:

1. The combination with a furnace movable 40 into a plurality of operating positions, of a stationary exhausting stack, a hood disposed upon said furnace for receiving gas passing from said furnace and having openings disposed at spaced positions in said hood for affording communication between said stack and said hood at each of 45 the positions of said furnace, and means for closing the openings when out of general alignment with the stack.

2. The combination with a furnace movable 50 into a plurality of positions, of a hood having spaced openings therein and disposed upon said furnace for receiving gas passing therefrom, a stationary stack, dampers disposed in the openings and when opened affording communication 55 between said stack and said hood through one of the openings at each of the positions of said furnace, means for opening the damper disposed in general alignment with the stock when the furnace is at rest, and means for holding another damper closed. 60

3. The combination with a furnace movable into a plurality of operating positions, of a stationary exhausting stack, a hood movable with the furnace and having openings positioned to afford communications between said stack and said hood when said furnace is moved into any one of the operating positions, a guide for said stack, and means for closing the openings in the hood when the openings are positioned out of general alignment with said stack. 80

4. The combination with a furnace movable into a plurality of operating positions, of a stationary exhausting stack, a hood movable with the furnace and having openings positioned to afford communications between said stack and said hood when said furnace is moved into any one of the operating positions, means for closing the openings in the hood when the openings are positioned out of general alignment with said stack, and means for actuating said closing means when moved into general alignment with said stack to move it into open position. 90

5. The combination with a furnace movable into a plurality of operating positions, of a stationary exhausting stack, a hood movable with the furnace and having openings positioned to afford communications between said stack and said hood when said furnace is moved into any one of the operating positions, means for closing the openings in the hood when the openings are positioned out of general alignment with said stack, and means carried by said stack for causing said closing means to be actuated when moved into general alignment with said stack to move it into open position, whereby gases may pass from said furnace, through said hood, the opening in alignment with said stack, and through said stack. 100

6. The combination with a furnace movable into a plurality of positions, of a stationary exhausting stack, and a hood having a plurality of exhaust ports and movable with the furnace to selectively align one of the exhaust ports with said stack for effecting communication between said stack and said furnace when said furnace 110 is moved into one of the positions.

7. The combination with a furnace movable into a plurality of positions, of a stationary exhausting stack, a hood having a plurality of exhaust ports and movable with the furnace to selectively align one of the exhaust ports with said stack for effecting communication between said stack and said furnace when said furnace is moved into one of the positions, and means for closing said exhaust ports when out of general alignment with said stack. 125
